CLAIM

The ornamental design for a door closer, as shown and described.

DESCRIPTION

FIG. 1 is a front, top, left side perspective view of a first embodiment of a door closer showing our new design; FIG. 2 is a front, bottom, right side perspective view of the first embodiment of the door closer; FIG. 3 is a top plan view of the first embodiment of the door closer;

FIG. 4 is a front elevational view of the first embodiment of the door closer; FIG. 5 is a back elevational view of the first embodiment of the door closer;

FIG. 6 is a bottom plan view of the first embodiment of the door closer;

FIG. 7 is a left side elevational view of the first embodiment of the door closer;

FIG. 8 is a right side elevational view of the first embodiment of the door closer;

FIG. 9 is a front, top, left side perspective view of a second embodiment of the door closer showing our new design; FIG. 10 is a front, bottom, right side perspective view of the second embodiment of the door closer;

FIG. 11 is a top plan view of the second embodiment of the door closer;

FIG. 12 is a front elevational view of the second embodiment of the door closer;

FIG. 13 is a back elevational view of the second embodiment of the door closer;

FIG. 14 is a bottom plan view of the second embodiment of the door closer;

FIG. 15 is a left side elevational view of the second embodiment of the door closer; and,

FIG. 16 is a right side elevational view of the second embodiment of the door closer.

The broken lines in the drawing figures form no part of the claimed design.

1 Claim, 10 Drawing Sheets
